ABSTRACT OF THE DISCLOSURE

The present invention relates to the regeneration of spent photographic bleach solutions by use of concentric electrodes with solution being circulated between the electrodes by the action of air.

BACKGROUND

In the processing of color photographic films, it is common practice to bleach out the silver image to silver bromide by a solution of an alkali bromide and alkali ferricyanide so that after processing is completed, only the dye image remains. The silver bromide is then removed in the fixing bath and washing steps which follow, leaving the dye image.

In this process the ferricyanide is converted to ferrocyanide.

Similarly, bleach solutions are also used in black and white reversal processes where their function is to remove the negative silver image so that upon completion of the processing, only the positive silver image remains.

Various means have been suggested for regenerating spent ferricyanide type bleach solutions used in photographic processing. Chemical regeneration techniques, such as the use of water soluble persulfates have been suggested. Such chemical oxidation techniques, however, offer the disadvantage of having to be done outside of the normal processing equipment, usually in a mixing tank after the processing tanks. Additionally, there is a danger of residual chemical oxidation which can seriously affect the color film processed.

As a means of further improving regeneration of bleach solutions, electrolytic means for oxidation of ferrocyanide back to ferricyanide have been suggested. Such systems have in general previously not been widely adopted due to relatively high capital investment and maintenance costs. Typical of such systems is the use of a porcelain or asbestos diaphragm between two electrodes with pumps for circulating the solution between the electrodes.

The present apparatus and process offers an extremely simple, adaptable, and low cost means for electrolytic regeneration of spent ferricyanide photographic bleach solution. More particularly, two general cylindrical electrodes are placed in a tank containing spent solution so as to have a substantial vertical orientation, i.e., either simply vertically, or at an angle inclined upwardly. The electrodes are concentric placed one within the other, with the outer electrode being copper and the inner electrode being carbon.

Typically, the inner electrode is a carbon rod and the outer electrode copper tubing, both of sufficient length, e.g., typically 12 to 36 inches to give a sufficient anode area, e.g., 0.5 to 2 square feet.

Electrical connections are connected to the top of the electrodes so as to make the outer electrode (copper) negative and the inside electrode (carbon) positive. If by chance the electrodes are incorrectly connected, no harm will be done since the copper electrode will quickly oxidize forming a copper oxide rectifier thereby stopping further passage of current, i.e., an automatic safety device.

2

Provision is made toward the bottom of the assembly for the introduction of air between the electrodes. The air serves to circulate the spent solution upwardly between the electrodes wherein ferrocyanide is converted to ferricyanide, with the air then serving to cause the regenerated solution to spill over the top of the outer electrode back into the tank reservoir. Enough air is passed between the electrodes so as to dilute the hydrogen gas given off during the electrolytic step thereby safeguarding against explosions, as well as sufficient agitation for promoting good flow of reactants to and from the electrode surfaces. Too much air is to be avoided since it will greatly limit the passage of current through the cell.

The use of air as opposed to pumps offers greater safety, reduced costs and better contact.

The high regeneration capacity (40 to 50 amperes per square foot), as well as compactness of the assembly (typically it can be a 3 inch diameter by 24 inches high unit, or less), make it suitable for installation in practically any place in the bleach system of the photographic process. Unlike chemical oxidation systems for regeneration, it can be installed in the circulation system of the bleach, or even in the process equipment. In further contrast with the residual oxidizing chemicals left in chemical regeneration, the present system allows the ferrocyanide level to be kept very low e.g., less than 0.1 gram per liter since the electrolytic regeneration is limited by the amount of ferrocyanide to be oxidized.

The various aspects and modifications of the present invention will be made more clearly apparent by reference to the following example, drawing and accompanying description.

DRAWING

The drawing shows the electrolytic system of the present invention for regeneration of spent bleach solution.

Turning to the drawing, shown therein is a tank 10 containing the bleach solution 11 to be regenerated. Because of its compactness, it may be placed in the bleach circulation system, or bleach circulated thereto by means of conduit 17 having valve 14.

Typical bleach solutions known in the art can be treated by the present invention. By way of example, a solution having the following composition based on one liter of solution has been found to be quite effective in processing all color films currently manufactured in the United States and abroad.

Water	700 ml.
Sodium or potassium ferrocyanide	54 grams.
Sodium or potassium bromide or chloride, or both, total amount	15 grams.
Sodium sulfate (anhydrous), add water to make one liter solution	14 grams.
Glacial acetic acid	Sufficient to adjust the pH to 4.5 during oxidation of the ferrocyanide to ferricyanide.

pH can be adjusted during regeneration by addition of HCl or HBr acid so that hydrogen ion as well as halides is supplied to the above formulation. In this event, part or all of the alkali bromide or chloride can be eliminated. In all events, the solution contains 15 grams/liter of halide, and its pH is adjusted to about 4.5.

In accordance with the present invention, positioned within tank 10 are two generally cylindrical electrodes. Outer electrode 16 is typically copper and inner electrode 15 is a carbon rod or cylinder.

A typical assembly employs a copper tube three inches in diameter, 24 inches long, and a carbon rod two inches

in diameter, which is also 24 inches long. This gives an anode area of about one square foot.

The tubes are connected to an electrical power source by connections 18, normally at their top portion, so that the outer copper tube is negatively charged, and the inner carbon tube positively charged.

Using a D.C. power supply of 3.2 volts, normal operating currents of from 40 to 50 amperes occur.

Use of a copper tube is necessary to convert nascent hydrogen to diatomic hydrogen due to the formation of Cu_2H_2 (copper hydride). Nascent hydrogen essentially does not exist due to this rapid conversion on the surface of the cathode so that ferricyanide formed at the anode is not converted to ferrocyanide. In contrast, prior art systems employ physically separate solutions by use of diaphragms.

Further, if the copper tube was reversed in charge, i.e. positively charged, it becomes a copper oxide rectifier with essentially no flow of current thereafter.

Air is introduced by one or more inlets 12 and 13 positioned so that the air moves up the annular passage 20 between the electrodes.

The electrodes are immersed in the spent bleach solution 11 in tank 10 so that the top of the electrodes is a short height, e.g., 4 inches, above the level 19 of solution to be regenerated. The air introduced into annular passageway 20 forces the liquid upwardly, forcing it to spill over the top of the outer electrode into the main body of the solution, thereby creating a constantly circulating stream of solution between the electrodes. The amount of air introduced is controlled carefully for best agitational circulation, as well as dilution of evolved hydrogen at the cathode to minimize danger of explosions. Too much air is undesirable since excessive agitation will greatly limit the passage of current through the cell.

In the example given, air is introduced at a rate of 0.5 ft.³/min. into the annular passage which is one inch in diameter.

While shown in vertical orientation, the electrodes can be inclined so long as sufficient vertical component in the annular passageway exists so that the air is allowed to move upwardly to cause circulation, and spillage of regenerated solution over the top of the electrode into the main solution reservoir.

However, while it might be expected that other possible configurations defining an elongated passageway other than cylindrical-shaped electrodes could be used, it has been found that flat plates or rods do not offer the advantages of the present system. Difficulty of obtaining uni-

form agitation, formation of pockets of hydrogen, and sludging with fouling of electrodes were encountered. It was difficult to use such flat plate configuration as a means of pumping solution.

Having described the present invention, that which is sought to be protected is set forth in the following claims.

What is claimed is:

1. In an electrolytic process for regenerating a spent photographic bleach solution containing ferrocyanide to be converted to ferricyanide, the improvement which comprises establishing an annular zone between an inner positively charged electrode and an outer negatively charged electrode positioned within a reservoir of spent bleach solution, introducing sufficient air upwardly through said annular zone so as to create a circulation of spent solution undergoing regeneration between the electrodes and to dilute evolved hydrogen so as to safeguard against explosion.

2. The improvement of claim 1 which further comprises flowing air so as to circulate spent bleach solution from said reservoir into and up said annular zone, and then returning regenerated solution over the top of the outer electrode back into said solution reservoir.

3. The improvement of claim 1 wherein the ferrocyanide level of the spent bleach solution is less than 0.1 gram per liter.

4. The improvement of claim 1 wherein operating currents of 40 to 50 amperes per square foot are used across said electrodes.

5. The improvement of claim 1 wherein air is introduced upwardly through the annular zone at a rate of 0.5 ft.³/min.
